GRAVE MARKER

Filed Oct. 16, 1924

Fig. 2. M. G. Slawson, Inventor

By Shepherd Campbell

Attorneys

UNITED STATES PATENT OFFICE.

MARION G. SLAWSON, OF GIRARD, KANSAS.

GRAVE MARKER.

Application filed October 16, 1924. Serial No. 744,034.

To all whom it may concern:

Be it known that I, MARION G. SLAWSON, a citizen of the United States, residing at Girard, in the county of Crawford and State 5 of Kansas, have invented certain new and useful Improvements in Grave Markers, of which the following is a specification, reference being had therein to the accompanying drawings.

10 This invention relates to grave markers and it has for its object to provide a simple and inexpensive device of this character constructed in such manner as to provide a novel and highly advantageous assembly 15 of the parts and one wherein the entry of rain or snow to the card carrying compartment will be effectually prevented.

Further objects and advantages of the invention will be set forth in the detailed description which follows.

In the accompanying drawings:

Figure 1 is a front elevation of a grave marker constructed in accordance with the invention.

25 Figure 2 is a view partly in side elevation and partly in vertical section.

Figure 3 is a fragmentary vertical sectional view.

30 Figure 4 is a detailed horizontal sectional view through the card holding frame, upon an enlarged scale, and

Figure 5 is a detail rear view of the lower portion of the cross and the upper portion of the stake hereinafter described.

35 Like numerals designate corresponding parts in all of the figures of the drawing.

The grave marker of the present invention comprises a rectangular sheet metal frame 5, the material of which is pressed outwardly at 6 to form a rectangular cavity within which a card holding frame 7, likewise of sheet metal, is adapted to have a seating. This card holding frame comprises the imperforate back plate 8, inturned ends 9, and downturned upper edge 10, these in-turned ends and upper edge holding in place a pane of glass 11, behind which an identification card 12 is placed. The downturned upper edge 10 and the inturned ends 9 are so arranged as to completely exclude the entry of rain or snow to the card. The lower edge 8 of the imperforate plate 8 of the card holding frame is inclined slightly forward so that when the card holding frame 5 is pressed into the cavity or recess 5^a

formed in the frame 5 by the forward bending of the material of said frame, said lower edge of the card holding frame will engage the rear face of the lower part of the frame 5 to close the pocket or cavity 5^a. The card holding frame is held in place without the use of extraneous fastening devices by the presence of the stake 13 which is preferably of channel formation and is pointed at the bottom, as indicated at 14. The stake 13 has two tongues 15 and 16 struck therefrom which tongues project forwardly and downwardly and are adapted to pass through openings or slots 18 and 19 formed through the frame 5. To permit of the ready insertion of tongues 15 and 16 through their openings the material of plate 5 is pressed outwardly, as is indicated at 20 and 21. By inserting the lower end of the tongues 15 and 16 through the openings 18 and 19 and drawing downwardly upon the stake with respect to the frame 5 until lower edge of frame 5 springs over a raised portion 13^a of stake 13, the stake is secured to said frame 5 and additionally the card supporting 70 frame 7 is bound in position within the cavity 5^a. After the parts are assembled the tongues 15 and 16 and particularly the latter are mashed or flattened down to insure the 75 firm interlocking, as described. A cross 22 75 is employed, if desired, and if said cross be employed it may be easily mounted upon the rest of the structure without the employment of rivets, solder or like fastening devices.

90 The cross that I prefer to use comprises a vertical part 23 of channel formation and a horizontal part 24, likewise of channel formation. The horizontal part is cut out, as indicated at 25, so that the main flat portions 23^a, 24^a of said vertical and horizontal parts may lie in direct contact with each other. Ears 26 left upon the edges of the cut out portion 25 of the horizontal part 24 of the cross pass through openings 27 of the vertical part and are then bent over, as illustrated in Figure 2 to secure the vertical and horizontal parts together.

95 A tongue 28 projects from the front face of the part 23 near the lower end thereof and is adapted to pass over the top of the stake and engage in the cavity behind the pressed out portion 20 of frame 5.

100 The lower end of the cross or crucifix is pointed and passed beneath a strap 30 struck 110

from the metal of the stake, after which said pointed end is bent outwardly and upwardly to insure against accidental dislodgment of the cross from the stake.

5. A tongue 13^x is struck from the stake and is adapted to stand outwardly and engage the lower edge of frame 5 to thereby hold the parts in the assembled relation described, when the frame 5 and associated parts have been properly and completely engaged by the stake.

That portion of the frame 5 immediately adjacent or constituting the edge of the sight opening through which the identification 15 card is visible is preferably curved slightly inward to make a tight fit with the front face of the glass pane if any water does get in past this edge, said water will run down over the glass but cannot reach the card.

20 The exclusion of rain or snow is further assured by the apron 18^a constituted by the lower portion of the back plate 8 of the card holding frame.

It is to be understood that the invention is 25 not limited to the precise construction set forth but that it includes within its purview whatever changes fairly come within either the terms or the spirit of the appended claims.

30 Having described my invention, what I claim is:

1. A grave marker comprising a frame, having a sight opening formed therein, a card holding frame seated in conjunction 35 with the first named frame, a stake, and interengaging means between said stake and the first named frame, said stake overlapping the card holding frame and holding it in place by its presence.

40 2. A grave marker comprising a frame, shaped to form a cavity surrounding a sight opening, a card receiving frame seated in said cavity, a stake adapted to extend across the rear face of the first named frame and 45 hold the card holding frame in place by its presence, and interengaging elements between the stake and the first named frame.

50 3. A grave marker comprising a rectangular sheet metal frame stamped to form a cavity surrounding a sight opening, a card holding frame adapted to receive a glass and an identification card, said card holding frame being seated in said cavity, a stake extending vertically across the rear face of the first named frame and binding the card holding frame in place in said cavity and interengaging tongues and slots formed on the stake and first named frame.

60 4. The combination with a rectangular sheet metal plate stamped to form a cavity of rectangular formation surrounding a sight opening, a card holding frame seated therein, a stake extending vertically across the card holding frame and holding it in 65 place and forwardly and downwardly di-

rected tongues carried by the said stake there being slots formed in the first named frame for the reception of said tongues.

5. A structure as recited in claim 4 in combination with means for preventing vertical 70 movement of the stake with respect to the first named frame.

6. A structure as recited in claim 4 in combination with a tongue upon the stake adapted to stand outwardly beneath and engage 75 the lower edge of the frame to hold said stake against vertical movement with respect to the frame.

7. A device of the character described comprising a plate having a sight opening 80 formed therein, a card holding frame adapted to have a seating in the rear of said sight opening and comprising overturned top and end edges and a transparent pane and an identification card held in place by said 85 overturned edges and a stake extending across the card holding frame and engaging the first named frame.

8. A structure as recited in claim 3 where- 90 in the stake is provided with a tongue adapt- ed to stand outwardly beneath the lower edge of the frame when the stake and frame have been moved a predetermined distance with respect to each other to thereby prevent reverse movement of the stake with respect 95 to the frame.

9. A structure as recited in claim 7 where- 100 in the inner edges of said sight opening are depressed to fit closely back against the transparent pane.

10. A structure as recited in claim 7 where- 105 in the overturned end and top edges of the card holding frame form a groove into which the identification card and transpar- ent pane slide and fit closely, leaving the face of said card holding frame open and the card visible, the back of said plate being imperforate.

11. A structure as recited in claim 7 where- 110 in the edges of the sight opening are in- wardly curved and wherein the interior ex- tremity of the overturned edges of the card holding frame fit closely up against the back of the inturned edges of the said sight open- ing in said front plate.

12. A structure as recited in claim 7 where- 115 in the overturned top edge of the card hold- ing frame overlap the overturned end edges of the said frame, thereby making the upper corners of said frame practically impervi- 120 ous to descending rain, water or snow, from the rear side of said frame.

13. A grave marker comprising a frame shaped to form a cavity surrounding a sight opening, a card holding frame adapted to 125 have a seating at the top and at each end of the said cavity from the rear thereof, the lower edge of said card holding frame ex- tending down over the lower edge of said cavity and shaped to bend slightly toward 130

said first mentioned frame, and being held in place by a stake across the back thereof and attached to said first frame by interengaging elements.

5 14. In a grave marker construction, a plate, a card carrying frame mounted in said plate, a stake holding said card carrying frame in place, a cross comprising a vertical element, and a member upon the cross adapted to extend over the top of the stake and engage in a recess of said plate to thereby hold the cross in place.

10 15. In construction, a front plate having a sight opening therein, and a card carrying frame seated upon the plate rearwardly of the sight opening, a stake which extends vertically across the rear face of the card carrying frame, tongues upon the stake engaging the plate by downward movement of

the stake with respect to said plate and a tongue on the stake adapted to stand outwardly beneath the lower edge of the plate and prevent reverse movement of the stake when the stake has reached its position of assembly with the plate.

25

16. A grave marker, a card carrying frame, a stake for supporting the same and a crucifix, the crucifix having a tongue struck therefrom adapted to engage the top of the stake and the stake having a part struck therefrom through which the lower portion of the crucifix passes and into engagement with which the lower portion of the crucifix may be bent.

30

17. In testimony whereof I hereunto affix my signature.

35

MARION G. SLAWSON.
